his Attorney.

UNITED STATES PATENT OFFICE.

JAMES H. PITTS, OF MCKEESPORT, PENNSYLVANIA, ASSIGNOR TO GARNET A. PITTS,
OF MCKEESPORT, PENNSYLVANIA.

SALES BOOK.

Application filed April 29, 1922. Serial No. 557,369.

To all whom it may concern:

Be it known that I, JAMES H. PITTS, a citizen of the United States, and resident of McKeesport, in the county of Allegheny and 5 State of Pennsylvania, have invented certain new and useful Improvements in Sales Books, of which the following is a specification.

This invention relates to manifold sales 10 books, and more particularly to books of this class for making triplicate sales records, and has for one of its objects the provision of a novel carbon sheet for such books.

Another object of the invention is the provision of a novel book of this class in which 15 one of the records will be made on both sides of a transparent sheet, thus providing a distinct record.

A still further object of the invention is to 20 provide a record on the transparent sheet that will effectively prevent alterations after it has been made.

The above and other objects and advantages will be more fully brought out in the 25 following specification and illustrated in the accompanying drawings, in which—

Figure 1 is a perspective view of a manifold sales book showing one embodiment of this invention.

Figure 2 is a plan view of the carbon sheet 30 employed in carrying out this invention.

Figure 3 is a diagrammatic line drawing illustrating the position of the several record sheets and carbon sheet when in operative 35 position.

Referring more particularly to the drawings, the numeral 2 designates the bottom cover of a sales book holder to which the top cover 3 is connected along one of its 40 longitudinal edges by a flexible hinge 4. At the opposite longitudinal edge of the bottom cover 2 is a second flexible hinge 5 for connecting an auxiliary back or support 6 therewith. The back or support 6 carries a record pad 7 for receiving the inscription, the pad comprising a plurality of sets of double leaves composed of original and 45 duplicate record sheets 8 and 9, respectively, divided by a line of perforations 10. The pad 7 is secured to support 6 by a spring 50 pressed clamping member 11 having teeth 12 adapted to engage the pad.

A triplicate pad composed of a back 13 and translucent or tissue leaves or inter-

sheets 14 is detachably secured to the bottom 55 cover 2 of the book by a binding catch 15.

A double length carbon member is bound in the pad 7 and comprises one length of double face carbon 16 and a second length of single face carbon 17. That is, a carbon sheet of twice the length of the record sheets is employed and is folded along its transverse center line. The upper face of the carbon sheet is provided with a carbon face for its entire length, while the lower face is provided with a carbon face for only one-half its length, thus leaving the lower half of its length bare, as at 18.

In practice the folded carbon member is folded upon itself so that the full length of 70 carbon is inside and forms opposite carbon faces, and the half length of carbon is on the bottom, and the carbon is interposed in this position between the original and duplicate record sheets 8 and 9. When it is desired to use the book, the original record sheet 8 and top half of carbon (the length of single carbon 17) is pulled upwardly 75 away from the duplicate sheet 9 and lower half of carbon, and one of the tissue sheets 80 or leaves 14 of the triplicate pad is interposed between the halves of the carbon sheet, and the top half of the carbon sheet and original record sheet are replaced over the tissue sheet. When thus positioned any inscription on the original record sheet 8 will be duplicated on both sides of the triplicate tissue sheet 14 and on the top side of the duplicate sheet 9. Thus a clear and distinct 85 copy is made on the tissue sheet 14, a good 90 duplicate copy is made, and the back of the original sheet 8 is kept clean and free of carbon.

Another feature of the double copy on the tissue is that such a copy is almost impossible to alter without detection, since the carbon cuts into the tissue from both sides and any alteration would be easily perceived.

While I have shown my invention applied to a manifold sales book it will be understood that I do not wish to be limited to such a book since the invention is applicable to any form of triplicate copy manifold books or pads, and many modifications of its application will readily suggest themselves to those skilled in the art.

I claim—

In a manifold sales book, a back, super-

posed sets of original and duplicate leaves secured to the back, a plurality of single tissue intersheets secured to the back adjacent one edge of the sets of leaves, and to be interposed singly between the original and duplicate leaves of successive sets, respectively, and a double face transfer sheet secured at one end of the said back and to be interposed between an intersheet and a 10 duplicate leaf with its transfer faces in cooperative relation with the upper side of the duplicate leaf and the underside of an inter-

posed intersheet, respectively, said double face transfer sheet having a longitudinal extension of that transfer face only which is to 15 be in cooperative relation with the underside of the said interposed intersheet, whereby, said extension may be folded back to lie between the original sheet and the intersheet with its transfer face in cooperative relation 20 with the upper face of the intersheet.

In testimony whereof I have hereunto signed my name.

JAMES H. PITTS.
